UNITED STATES PATENT OFFICE

2,199,476

CARTON

Edward C. Berg, Chicago, Ill., assignor to Ace
Carton Corporation, a corporation of Illinois

Application January 3, 1938, Serial No. 183,068

2 Claims. (CL. 206—42)

The present invention relates generally to a carton or paper container, but more particularly to a novel and improved carton of the tray type which is adapted to contain therein fragile or crushable merchandise.

The primary object of the present invention is to provide a novel, compact and economical construction of a tray-type carton for holding merchandise of fragile nature in separated or spaced apart position.

A further object of the invention is to provide a novel and improved tray-type carton in which the material necessary to produce the same is reduced to a minimum so as to produce a relatively light carton and yet at the same time contains sufficient strength to hold merchandise of a fragile nature.

A further object of the invention is to provide a novel and improved construction of a capsule carton in which means are provided to facilitate the removal of a capsule from the recesses in the tray.

These and other objects are accomplished by providing a construction and an arrangement of the various parts in the manner hereinafter described and particularly pointed out in the appended claims.

Referring to the drawing:

Fig. 1 is a perspective view of my improved carton;

Fig. 2 is a cross sectional view taken on the line 2—2 of Fig. 1;

Fig. 3 is a longitudinal cross sectional view taken on the line 3—3 in Fig. 2;

Fig. 4 is a top plan view showing the manner in which the protective flap and tray holder is made of one single piece of cardboard;

Fig. 5 is a longitudinal cross sectional view of a novel form of flexible tray which facilitates the removal of the capsules therefrom;

Fig. 6 is a cross sectional view of the tray holder and tray shown in Fig. 5; and

Fig. 7 is a cross sectional view taken on the line 7—7 in Fig. 5.

The present invention is an improvement over my U. S. Letters Patent No. 2,057,180 granted the 13th day of October, 1936.

In illustrating one form of the present invention, I have shown the same in connection with a tubular telescoping cover generally indicated by the reference character 10 which is opened at both ends and is provided with a window or opening 11 through which the material contained therein can be seen. The principle feature of the present invention includes the simplicity of con-

struction by reason of which unnecessary parts and materials are reduced to a minimum and includes a tray holder and protective flap made of a single piece of material as generally indicated by the reference character 12 in Fig. 4 of the drawing. This single flat piece of cardboard includes a tray holder section 13 and protective flap 14. These main sections 13 and 14 are connected by a strip 15 which forms one end of the container proper and is foldable on the scored lines 16 when the same is inserted in the telescoping cover 10. The protective flap 14 performs the function of preventing the capsules from being dislodged from their recesses as the tray is moved with respect to the cover. This flap 14 is scored on transverse lines 17 so that the same may be folded upwardly for securing access to the material within the tray in the manner clearly disclosed in Fig. 1 of the drawing. The flap 14 is further provided with an opening or window 18 extending longitudinally thereof in substantial alignment with the window 11 of the cover 10. This window 18 is covered by translucent material such as Cellophane as indicated by the reference character 19. The tray holder section 13 is provided on one end thereof with a tuck-in flap as shown at 20 which is connected to the section 13 by an end wall 21. The same is foldable on the transverse scored line 22 so as to form the enclosed end in the manner clearly shown in Fig. 3 of the drawing. The tray in this instance comprises a relatively thick board made of any suitable material such as wood pulp which has the bottom surface adjacent the ends thereof glued or otherwise secured to the tray holder section 13. The tray 23 is provided with a plurality of regularly arranged punched holes or recesses 24 for the reception therein of fragile material such as capsules and the like.

Another novel feature of this construction includes relatively small apertures 25 extending through the tray holder section 13 arranged concentrically of the recesses 24 in the tray so that in the event the capsule adheres to the side walls of the recess as the result of weather conditions, a portion of the finger or any suitable object may be projected into the holes from the bottom of the tray holder section to force the capsule upwardly out of the recess and facilitates its removal therefrom.

In the modified form of my invention shown in Figs. 5 to 7 inclusive, the same telescoping cover 10 is employed and the same tray holder section 13 and protective flap 14 are used. The

novelty in this modified form includes a flexible or depressable capsule tray which comprises a lower perforated mat 26 which is provided with uniformly spaced apart perforations 27. The 5 opposite ends of the perforated mat 26 is folded completely against itself as shown at 28 with the lower surface of the folded portion glued or otherwise secured to the opposite ends of the tray holder section 13, thus spacing or holding the intermediate portion of the mat in spaced 10 relation with respect to the tray holder 13. Positioned above the lower mat is a second perforated mat 29 which is similarly provided with uniformly spaced perforations 27 in the mat 26. This 15 perforated mat 29 is similarly provided with inwardly bent ends 31, which in turn, have their undersides glued or otherwise secured to the opposite ends of the lower mat 26, to thereby space the intermediate portions of the upper mat 20 with respect to the lower mat. The concentrically arranged perforations 30 and 27 of the respective mats 29 and 26 are also arranged concentrically with respect to the perforations 25 of the tray holder section 13 so that when the 25 flexible tray constituting the two perforated mats 29 and 26 is depressed, sufficient grip on the capsules may be had by depressing the mat in the manner shown in Fig. 6 to facilitate removal of the capsules from the respective recesses. The 30 perforations 25 in the mat holder 13 permit a portion of the finger or other object to be inserted to further assist the removal of the capsules therefrom.

Summarizing the functions and advantages of 35 my improved capsule carton, it will be readily seen that by making the tray holder and protective flap from a single rectangular strip of cardboard and securing the tray directly to the tray holder section, I have not only reduced the amount of material and weight necessary to 40 construct this type of carton, but also have provided a simple, compact as well as economical carton which can be quickly and easily assembled with a minimum of effort. It will also be noted that by forming the capsule tray with two 45 spaced apart mats so that they may be flexibly depressed to a position in which the thumb and forefinger may grip the capsule, I have provided

means for quickly and easily removing the same therefrom. The apertures in the tray holder beneath the recesses further facilitate the removal of the capsule when the tray is partially removed from the telescoping cover. 5

While in the above specification I have described one embodiment and one modification of my invention, it will of course be understood that the same is capable of other modifications and such modifications may be made without 10 departing from the spirit and scope of the invention as expressed in the following claims.

What I claim is my invention and desire to secure by Letters Patent is:

1. A carton comprising a flat tray holder, a 15 tray including a perforated mat having its opposite ends bent rearwardly against the mat proper, said rearwardly bent portions being secured to said tray holder, a second perforated mat having its opposite ends bent rearwardly against the 20 mat proper, said bent portions being secured to said first named mat, both of said mats having uniformly spaced apart perforations therein in concentric alignment, the intermediate portion of said mats being spaced from each other and 25 from said tray holder whereby said mats are depressable by finger pressure adjacent said perforations to facilitate the removal of capsules therefrom, and a protective flap formed integrally with said holder for covering the articles contained therein. 30

2. A carton comprising a single flat tray holder, and a tray including a plurality of perforated mats secured at their opposite ends to said holder and spaced apart from one another and from 35 said holder, both of said mats having a plurality of uniformly spaced apart perforations therein with corresponding perforations therein with concentric alignment, said mats being depressable adjacent said perforations to permit finger pressure in facilitating 40 the removal of said capsules from said perforations, said holder having relatively smaller perforations therein adjacent the perforations in 45 said mats to facilitate the removal of articles from said tray.

EDWARD C. BERG.
